SCORE CARD

Homer M. Schubert, Salem, Oreg.

Application February 18, 1942, Serial No. 431,455

2 Claims. (Cl. 116—120)

This invention relates to score cards and is primarily intended to be used for keeping score in football games.

The primary object of the invention is to provide a card having the football field lines printed thereon, and having a movable indicator to be shifted over the field on the card indicating the position of the plays being made by the players.

As the football game is in progress the observer possessing one of these cards places the indicating device on the card to correspond with the players' positions on the field. This indicating device indicates which team has the ball in its possession. As the different plays are made a removable score card is provided for recording these plays.

A further object of the invention is to provide a space on the card for advertising purposes.

These and other incidental objects will be apparent in the drawing, specification and claims.

Referring to the drawing:

Figure 1 is a plan view of my new and improved score card.

Figure 2 is an enlarged detail view of the indicating device for indicating the position of the players on the field.

Figures 3 and 4 are another preferred form of indicator.

In the drawing:

My new and improved score card consists of a sheet of cardboard 1, having the goal posts 2 and 3 indicated thereon, also the yardage lines 4 are marked on the face of the card. A renewable score card 5 is held in place by the clips 6.

My invention consists of an indicating device 7 for indicating the position of the plays being made on the football field, and this indicating device indicates which of the teams are in possession of the ball. Players 8 and 9 represent the opposing teams.

Figure 2 shows the player 8 representing one of the teams in possession of the ball 10. The ball 10 is secured to an arm 11 pivotally mounted to the base 12 at 13. As the plays on the field are being executed the indicator 7 is located on the score card 1 relative to the yardage lines 4 to correspond with the plays. The indicator football 10 is shifted to the proper character 8 or 9 on the indicating device, therefore, at all times the observer of the game knows exactly what play has been made relative to the new position to be indicated.

Another form of indicator is illustrated in Figures 3 and 4, and consists of a base 14, having players 15 and 16. Figure 3 shows the player 15

possessing a definite color 17, and the player 16 having another color 18. These colors represent the different teams being scored. Figure 3 shows the indicating player 15 in possession of the ball 19. On turning the indicator, shown in Figure 3, over or upside down, it would appear as shown in Figure 4. The indicating player 15 then possessing the color shown on the player 16 in Figure 3, thereby indicating that the player 16, as indicated in Figure 3, is now in possession of the ball. The color 17 of the player 16, as illustrated in Figure 4, now represents the color of the player 15 as indicated in Figure 3.

This form of indicator is very simple of construction and very effective in indicating who is in possession of the ball, and the location of the players on the field. As the points are made by the players on the field these scores can be recorded on the removable score card 5, as indicated by the position of the players indicated by the indicator 7.

I do not wish to be limited to the exact mechanical construction, as other equivalents may be used, still coming within the scope of the claims.

What is claimed as new is:

1. A score card for football or similar games, marked in simulation of the markings of the playing field to represent different plays of the game, and an indicator to be manually moved to any position on the playing field on the card in correspondence with any particular immediate play on the field, the indicator presenting two figures distinctly representing the respective playing teams, and a ball movable at will through a predetermined path and relative to each figure, whereby to place the ball at will in simulated possession of either figure to indicate possession of the ball by the team represented by that figure.

2. A score card for football or similar games, marked in simulation of the markings of the playing field to represent different plays of the game, and an indicator to be manually moved to any position on the playing field on the card in correspondence with any particular immediate play on the field, the indicator presenting two figures distinctly representing the respective playing teams, an arm pivoted between the figures, and a ball carried by the arm, whereby to permit movement of the ball to a position adjacent either figure to indicate possession of the ball by the team represented by the selected figure.

HOMER M. SCHUBERT.
